UNITED STATES PATENT OFFICE.

ETIENNE FAJON, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 13,858, dated April 17, 1883.
Application filed March 12, 1883. Term of patent 8½ years.

To all whom it may concern:

Be it known that I, ETIENNE FAJON, of Boston, in the county of Suffolk and State of Massachusetts, have invented a new and original 5 Design for Carpets, of which the following is a specification.

The nature of my design is fully shown in the accompanying photographic illustration.

The design is composed of the aquatic scene 10 a, the floral and foliage ornamentation massed above the aquatic scene, the light center b above said floral and foliage ornamentation, and the variously-ornamented border and detached portions of groundwork, as shown.

I claim—

The design for a carpet, substantially as shown and described.

In testimony whereof I have signed my name to this specification in the presence of two subscribing witnesses.

ETIENNE FAJON.
